[57] CLAIM

The ornamental design for a cosmetic puff dispenser, as shown and described.

DESCRIPTION

FIG. 1 is a left-front isometric view of a cosmetic puff dispenser showing my new design;

FIG. 2 is a plan view thereof;

FIG. 3 is a front elevational view thereof;

FIG. 4 is a bottom view thereof;

FIG. 5 is a rear elevational view thereof;

FIG. 6 is a right side elevational view thereof;

FIG. 7 is a left side elevational view thereof; and

FIG. 8 is a section along line 8—8 of FIG. 1.

FIG.2
